DESIGN FOR A CABINET FOR DISPLAYING, STORING AND DISPENSING OILCLOTH, OR THE LIKE

Karel H. Toll, Passaic, N. J.

Application September 27, 1934, Serial No. 53,407

Term of patent 7 years

To all whom it may concern:

Be it known that I, Karel H. Toll, a citizen of the United States, residing in the city and county of Passaic, and State of New Jersey, have invented a new, original, and ornamental Design for a Cabinet for Displaying, Storing and Dispensing Oil Cloth, or the like, of which the following is a specification, reference being had to the accompanying drawing, forming a part thereof.

In the drawing, Fig. 1 is a perspective view of the cabinet, showing my design. Fig. 2 is a perspective view, with one of the doors opened to show the shelves and receptacles in which the articles to be displayed, stored, and/or dispensed are placed.

I claim:

The ornamental design for a cabinet for displaying, storing and dispensing oil cloth or the like, as shown and described.

KAREL H. TOLL.
